[57] CLAIM

The ornamental design for a sample holder for a vibrating viscometer, as shown and described.

DESCRIPTION

FIG. 1 is a perspective view of the sample holder for a vibrating viscometer showing my new design;
FIG. 2 is a side elevational view thereof with the opposite side elevational view being a mirror image;
FIG. 3 is a righthand end view thereof; and,
FIG. 4 is a lefthand end view thereof.

FIG. 1

FIG. 2

FIG. 3

FIG. 4
